Patented Aug. 19, 1913.

UNITED STATES PATENT OFFICE.

ANNIE L. STEVENS, OF FRESNO, CALIFORNIA.

DOLL.

1,070,553.

Specification of Letters Patent. Patented Aug. 19, 1913.

Application filed April 11, 1911. Serial No. 620,492.

To all whom it may concern:

Be it known that I, ANNIE L. STEVENS, a citizen of the United States, residing at Fresno, in the county of Fresno and State 5 of California, have invented certain new and useful Improvements in Dolls, of which the following is a specification.

This invention relates to dolls, and more particularly to that class of dolls commonly 10 known as cloth or rag dolls.

One feature of the invention resides in the peculiar formation of the ears of the doll and the manner in which they are connected to the sections of the head.

15 A still further object of the invention is generally to improve this class of devices, so as to increase their utility, durability and efficiency.

Further objects and advantages will appear in the following description, it being understood that various changes in form, proportions and minor details of construction may be resorted to within the scope of the appended claims.

25 For a full understanding of the invention and the merits thereof, reference is to be had to the following description and accompanying drawings, in which:

Figure 1 is a perspective view of a doll 30 embodying the present invention; Fig. 2 is a similar view, looking at the rear of the doll; Fig. 3 is a detail sectional view through one of the ears of the doll.

Corresponding and like parts are referred 35 to in the following description and indicated in all the views of the drawings by the same reference characters.

The improved doll forming the subject matter of the present invention is constructed from a pattern or blank formed of cloth, fabric or other suitable material, and comprises a breast or front piece 5, made in two sections, and a back piece 6, also preferably made in two sections.

45 The head of the doll comprises a face section 7 and back section 8, the latter being formed in two parts and connected with the face section by side head sections 9. The lower ends of the side head sections 9 are re-

duced at 10 and secured to the face section 7 50 and adjacent breast sections 5 to form the neck of the doll, while the back head sections 8 are secured to each other and to the upper edges of the adjacent back sections 6.

The ears of the doll are each preferably 55 formed in two sections 11, the outer edges of the sections comprising each ear being stitched or sewed at 12 and the inner edges thereof separated at 13 and inserted between the face section 7 and the adjacent side head 60 sections 9. The material forming the sections of each ear is preferably folded at 14 to imitate the lobe of a natural ear, the same row of stitching which secures the face section 7 to the side head sections 9, serving to 65 retain the ear sections in position on the head of the doll.

Having thus described the invention, what is claimed as new is:

1. A cloth doll including a body-portion, 70 a head secured to the body-portion and including sections stitched together at the sides of the head, and ear sections each formed in two pieces having their peripheral edges partly united, the separated edges of the ear 75 sections being interposed between the sections of the head and secured therebetween by the stitching uniting the said sections at the side of the head.

2. A cloth doll including a body-portion, 80 a head secured to the body-portion and including sections stitched together at the sides of the head, and ear sections each formed in two pieces having their peripheral edges partly united, the separated edges of the ear 85 sections being interposed between the sections of the head and secured therebetween by the stitching uniting the said sections at the side of the head, the said ear sections being each folded along a diagonal 90 line and stitched beneath the fold to one of the said head sections.

In testimony whereof, I affix my signature in presence of two witnesses.

ANNIE L. STEVENS. [L. S.]

Witnesses:

DAISY BELLE ROHRING,
W. E. PATTERSON.
